FIG. 5.

FIG. 6.

FIG. 7

INVENTOR.
Marcus Blumenfeld
BY *Gottlieb P. Blumenfeld*
ATTORNEY

UNITED STATES PATENT OFFICE

MARCUS BLUMENFELD, OF NEW YORK, N. Y.

SAFETY NIPPLE

Application filed June 15, 1928. Serial No. 285,665.

This invention relates generally to a baby's bottle, and has more particular reference to a novel nipple therefor.

The invention has for an object the provision of a device of the class mentioned, which is of simple durable construction, desirable and efficient in action, and which can be manufactured and sold at a reasonable cost.

10 The invention proposes the use of a nipple having a stopper portion for insertion into the mouth of a baby's bottle, and a flange portion arranged for engaging over and disengaging from the neck of the said bottle. In its normal disengaged position the flange is directed upwardly and around the main portion of the nipple, and it may be turned downwards for engaging the neck of the baby's bottle.

20 One of the main advantages of this arrangement is that the nipple is firmly held in place on a baby's bottle by reason of the stopper and the flange, this obtaining a positive and reliable connection. In addition 25 leaking of milk from the bottle is highly improbable due to the roundabout path necessary to travel for leaking. First the milk would have to pass along one direction and along the stopper, and then in the opposite 30 direction and along the flange.

For further comprehension of the invention, and of the objects and advantages thereof, reference will be had to the following description and accompanying drawings and 35 to the appended claims in which the various novel features of the invention are more particularly set forth.

In the accompanying drawing, forming a 40 material part of this disclosure:

40 Fig. 1 is a side elevational view of a baby's bottle provided with a nipple constructed according to this invention.

Fig. 2 is a fragmentary vertical sectional 45 view thereof.

Fig. 3 is a similar view showing the flange of the nipple in raised position.

Fig. 4 is a side elevational view of a baby's 50 bottle provided with a nipple constructed according to a modified form of the invention.

Fig. 5 is a fragmentary vertical sectional view thereof.

Fig. 6 is a similar view showing the flange of the nipple in a lowered position.

Fig. 7 is a fragmentary side elevational 55 view of a baby's bottle provided with a nipple of modified form.

Fig. 8 is a view similar to Fig. 5, but illustrating a modified form of the invention.

The reference numeral 10 indicates generally a baby's bottle having a mouth 11 within a neck 12 which has an enlarged top edge 13.

Engaged in the mouth 11 is a stopper portion 14 of a nipple having a main body 15 and an integral flange 16 arranged for engaging over the neck 12, or for being turned upwards as shown by the dot-dash lines 17 in Fig. 2, and by full lines in Fig. 3. The stopper portion 14 is formed with an aperture 18 provided with a flexible tubular projection 14' adapted to receive one end of a tube 19 which extends to a small distance from the bottom of the bottle 10.

When the bottle is laid on its side, the end 75 of the tube 19 near to the bottom of the bottle 10 hangs down toward the lower edge of the bottle, thereby allowing most of the milk to be sucked out of the bottle.

In applying the nipple on a bottle, the flange 16 should be turned into raised position, and then the stopper 14 forced into the mouth of the bottle. Next the flange 16 should be turned down over the neck of the bottle.

Suitable air holes 15' are provided in the 85 nipple preferably near the stopper portion 14.

In Figs. 4, 5 and 6, the tube 19 is eliminated from the device, and the flange 16' is formed with a groove 20 for engagement over the enlarged end 13, and with a bulge 21 for 90 engagement against the side of the neck 12. This organization provides a finer fit of the nipple upon the bottle, and acts for further insuring against milk leakage from the bottle.

In Fig. 7 small integral flaps 22 are shown 95 connected on the flange 16 for providing a gripping element for raising and lowering the flange.

The modified form shown in Fig. 8, discloses a comparative non-elastic flange 24, 100

relative to the material of the nipple, such as rubberized cloth, secured to the top of the stopper 14 by reason of having its ends cast into the stopper, and arranged for engaging 5 over the neck 12 of the bottle. The flange 16 engages over the flange 24, when turned downwards for forcing the flange 24 firmly against the neck 12. This arrangement also prevents leakage of milk from engaging against the 10 flange 16.

While I have shown and described the preferred embodiment of my invention, it is to be understood that I do not limit myself to the precise construction herein disclosed 15 and the right is reserved to all changes and modifications coming within the scope of the invention as defined in the appended claims.

Having thus described my invention, what I claim as new and desire to secure by United 20 States Letters Patent is:

1. A nipple for a baby's bottle having a neck with an enlarged top edge, and a mouth, comprising a main portion, a stopper portion integral therewith and engageable in the said 25 mouth, an integral flange engageable over the neck of the bottle, and a comparative non-elastic flange attached to the stopper and engageable over the neck of the bottle beneath the said flange.

2. A nipple for a baby's bottle having a neck with an enlarged top edge, and a mouth, comprising a main portion, a stopper portion integral therewith and engageable in the said mouth, an integral flange engageable over the 35 neck of the bottle, and a comparative non-elastic flange attached to the stopper by reason of having its edges cast into the material of the stopper and engageable over the neck of the bottle beneath the said flange.

3. A nipple for a baby's bottle having a neck with an enlarged top edge, and a mouth, comprising a main portion, a stopper portion integral therewith and engageable in the said mouth, an integral flange engageable over the 45 neck of the bottle, and a comparative rubberized cloth flange attached to the stopper and engageable over the neck of the bottle beneath the said flange.

In testimony whereof I have affixed my 50 signature.

MARCUS BLUMENFELD.
